LISTING CALCULATOR

Loring P. Crosman, Maplewood, N. J., assignor,
by mesne assignments, to Monroe Calculating
Machine Company, Orange, N. J., a corporation
of Delaware

Application June 19, 1936, Serial No. 86,073

2 Claims. (Cl. 235—60)

The invention has relation to listing calculators and more particularly to means for temporarily modifying the action of a program mechanism controlling the activity of and the sign character of registration upon a plurality of accumulators.

5 The invention consists in the novel construction and combination of parts, as set forth in the appended claims.

The invention is shown as applied to a calculating machine constructed in accordance with the disclosure of my U. S. Patent No. 1,932,013, issued October 24, 1933, and entitled "Registers", the program mechanism employed being in accordance with the disclosure of my U. S. Patent 15 No. 1,946,572, issued February 23, 1934, and entitled "Listing calculators."

In the accompanying drawings, illustrating the invention:

Fig. 1 is a right side elevation of the accumulating and printing mechanism of a machine to which the invention is shown as applied, the parts being broken away.

Fig. 2 is a similar view of the accumulator controlling mechanism.

25 Fig. 3 is a right side elevation of the program mechanism, with parts broken away.

Fig. 4 is a detail right side elevation of parts shown in Fig. 3 in a different position of adjustment.

30 Fig. 5 is a rear elevation of a part of the program mechanism, with parts broken away.

Fig. 6 is a detail side elevation of a program plunger, and associated parts.

Fig. 7 is a detail plan view of the plunger block-35 ing cylinder.

Accumulation

Referring to Fig. 1, amounts set on the keys 215 are registered in the accumulators No. 1, No. 2, 40 No. 3 and No. 4 upon operation of an electric motor 100 having driving connection with rock shaft 301, which is connected with a frame 616 by means of spring held latching dogs 617. Reciprocation of shaft 301 by operation of motor 100 will therefore rock the frame 616, first in a counter-clockwise direction as viewed in Fig. 1, allowing segments 610 to move counter-clockwise about shaft 608, and thereafter the return movement of shaft 301 will effect clockwise movement of the parts. The extent of these movements is determined by engagement of a stop bar 615 pivotally connected to the segments 610, with the end of a depressed key 215. The segments 610 related to key columns wherein no key has been 50 depressed are held inactive by means of zero stops

214. The various movements of the segments 610 in a counter-clockwise direction has served to adjust printing type mounted on type bars 611 pivotally connected to the segments 610, this movement serving to bring type representing the appropriate digits to the printing line.

Means are also provided for throwing the pinions of accumulators No. 1, No. 2, No. 3, and No. 4 into mesh with the segments 610 either during the forward stroke of said segments, to effect subtractive registration on the accumulators, or during return stroke of the segments to effect additive registration thereon. This means comprises a series of cams on the register shafts 403 and a series of cooperating cams connected with rocker plates 419 (Fig. 2) so arranged that when the high points of the cams upon the shaft 403 register with the high points of the cams connected with the plates 419, the register pinions will be moved into mesh with the segments 610, against the tension of suitable springs, the register shafts being guided in the movements into and out of mesh with the segments by engagement with the walls of suitable slotted recesses in a fixed frame plate.

25 As shown, the two upper accumulators, No. 1 and No. 2 are capable of additive or subtractive registration, while the No. 3 and No. 4 accumulators are designed for addition only. Any of the accumulators may be disabled, or adjusted to non-add condition by appropriate location of the cams carried by the shafts 403.

In order that the No. 1 and No. 2 accumulators may be set for addition or subtraction, the shafts 403 of these accumulators are provided with two cams 121 and 122 projecting from the shaft in different angular directions. Thus rotation of shaft 403 will move the cams 121 out of registering position and the cams 122 into registering position, a further rotation of the shaft moving both cams out of registering position. Two plates 419 are shown, connected by a pin and slot device for movement in opposite directions. Each plate 419 is provided with cams 124, lying in the plane of and cooperating with the cams 122, and cams 45 438, lying in the plane of the cams 121. The plates 419 are rocked to change the position of the cams 124 and 438 relative to their cooperating cams at the end of the forward stroke of the segments, and may also be rocked at the beginning 50 of the registering operation, one of the plates 419 having link connection with a rocker 325 for this purpose. Rocker 325 is controlled by two cam arms 316 and 320, secured upon rock shaft 301, the arm 316 being adapted to engage a cam fol-

lower pivoted upon the rear end of rocker 325 and arm 320 adapted to engage a similar cam follower pivoted upon the forward end of the rocker. Fig. 2 illustrates rocker 325 in its condition of normal operation, in which adjustable plate 326 is so positioned as to prevent counter-clockwise pivotal movement of the rear cam follower and to prevent clockwise pivotal movement of the forward cam follower, this plate being adapted to rock with rocker 325. At the beginning of a registering operation cam arm 320, contacting the forward cam follower will move the rocker 325 in clockwise direction as viewed in Fig. 2, rocking the plates 419 to bring the cams 124 thereof into registering position. In Fig. 2 the cooperating cam 122 is in inactive position, and, since the cam 438 was moved away from cam 121 by the rocking of plate 419, the No. 1 accumulator will be allowed to move out of mesh with the segments, and no subtractive registration will occur therein. No. 2 accumulator however is set with cam 122 in operative position, and the rocking of plate 419 will bring cam 124 into contact with cam 122, so that the No. 2 accumulator will be thrown into mesh and subtraction will be effected. In the beginning of the return stroke of the cam arms 316, 320, arm 316 will contact with the rear cam follower and will move the rocker 325 back into the position illustrated in Fig. 2, wherein the cams 124 will be moved to inactive position and the cams 438 into active position, so that addition will be effected on the No. 1 accumulator, while the No. 2 accumulator is allowed to move out of mesh.

The No. 3 and No. 4 accumulators are provided with cams 135 made each in the form of a disk having a flattened side 136. In Fig. 2 the flattened side 136 of the cams 135 are shown as lying opposite the cooperating pawls 137, so that no registration of these accumulators No. 3 and No. 4 will be effected. One of the pawls 137 has link connection with one of the plates 419, and also engages at its free end with the free end of the other pawl, so that upon movement of the plates 419 both of these pawls will drop away from the cams 135, and will be returned into the position shown in Fig. 2 at the beginning of the return stroke of the segments. Therefore, if the cams 135 have been adjusted to bring their semi-cylindrical walls opposite the pawls 137, the No. 3 and No. 4 accumulators will be moved into mesh at this time and addition will be effected.

Total taking

The total standing in any one of the registers may be cleared therefrom and printed on the record sheet by engaging the pinions 472 of the register with the segments 610 and moving the segments subtractively until zero stops 457 of the register units engage cooperating stops 613 which have been brought into their path of movement. This serves in well known manner to subtract the total from the register and to set it in the type bars 611.

The total key 218 which controls this operation is designed to reverse the effective action of the cams 124 and 438, so that a register which has been adjusted for additive accumulation will need no adjustment when a total is taken therefrom. For this purpose a projection of the total key lever engages a pin 352 on the plate 326, and readjusts said plate relative to rocker 325, this readjustment bringing the lower hook end of plate 326 in front of the pin in the upper end of the forward cam follower and removing the shoulder

of said plate from engagement in rear of said pin. A cam face plate 326 also engages a pin in the upper end of the rear cam follower and rocks said follower pivotally out of the path of movement of cam arm 316.

Therefore, during a total taking operation cam arm 320 will rock the forward cam follower pivotally during the forward stroke, without moving the rocker 325, thereby leaving the cams 438 opposite the cams 121. During the return stroke of the segments, cam arm 320 will engage the forward cam follower and move the rocker 325 and plates 419 to remove the cams 438 from engagement with the cams 121, so that the registers which are set for additive accumulation will move out of mesh with the segments. Accumulators in which the cams 122 had been set to active position during the taking of the total from another accumulator will be thrown into mesh during the second or additive stroke of the segments, and will accumulate the total cleared from said other accumulator.

In the machine illustrated, the upper or No. 1 accumulator is a "cross footer", designed to accumulate the values entered into each of the other accumulators during a single series or line of entries. No. 2 accumulator is customarily a debit register, and is set for subtractive operation, it being noted that a complementary value will stand on this No. 2 accumulator, and that the addition of this complementary value to another (the No. 1) accumulator during the taking of a total will be equivalent to the subtraction of the true amounts registered in No. 2 accumulator from the amounts registered in No. 1 accumulator. Thus a "vertical total" or a total of all of the entries in each of the accumulators No. 2 to No. 4 may be taken, these totals being transferred to the No. 1 accumulator to show a grand total.

Program mechanism

Means are provided for setting the various accumulators to add, subtract or non-add, in accordance with the tabular position of the record carriage. This comprises means for rotating the register shafts 403 to position the cams 121, 122, and 135 to the desired positions. For this purpose a perforated tube 82 (Figs. 3 and 5) mounted in the transverse and shiftable record carriage cooperates with feeler devices in the frame of the machine. The feeler devices include plungers 83 and 84, designed to register with the perforations of the tube 82. The plungers 83 related to No. 1 and No. 2 accumulators are provided with reduced end portions, joined to the body of the plungers by shoulders. The perforations in the tube 82 are of two sizes, corresponding to the reduced and enlarged portion of the plungers 83, the larger perforations also corresponding to the diameters of the plungers 84.

The plungers being moved toward the tube 82 will be immediately arrested, if no perforation of said tube is in line with the plunger, whereas if a large perforation of the tube 82 is opposite the plunger, said plunger will move freely to its full extent of movement. If a small perforation of the tube 82 is opposite one of the plungers 83, the shoulder of the plunger will contact with the marginal walls of the perforation and the plunger will be held in an intermediate position.

The plungers 83 and 84 are mounted upon intermediately pivoted levers 86, the opposite ends of these levers being connected by links 96, levers 93 and yieldable spring connections 94 with plates 77.

69. Plates 69 are rocked through link 67 and crank arm 58 secured upon a rotary shaft 56 capable of being driven from the motor 100. Upon operation of shaft 56 therefore the plungers 83, 84 will be moved rearward toward tube 82, and will be positioned by abutment with said tube in one of three positions. Levers 93 are provided with lugs 98, these lugs taking one of three positions, in accordance with the position of the related plunger, so that the lugs are brought under the surface 99 of a dog 74, under the surface 102 of a dog 73 or to a position immediately beneath a shaft 116 supporting the dogs 73 and 74. Normally dogs 73 and 74 are locked in position by engagement of a roller 71 of the plate 69 with the upper or with the lower surface of the dogs. Upon movement of the plate 69 however roller 71 will be moved out of engagement with the dogs 73, 74, and these dogs will be allowed to assume the position illustrated in Fig. 3, under the influence of a connecting spring. However, if the lug 98 of a lever 93 has been positioned by the related plunger under the surface 99 of dog 74, the spring 94 will cause the dog to be moved downwardly, until the point of the dog lies below roller 71. Continued rotation of shaft 56 will rock the plate 69 in an opposite direction, and the roller 71 acting upon the dog 74 will bring the dogs into the position illustrated in Fig. 4. Contact of lug 98 with surface 102 of dog 73 will position said dog so that it will be moved upwardly by action of roller 71. Dog 73 contacts with a lug 113 of a segment 105, and dog 74 contacts with an opposite lug 115 of said segment. Therefore the positioning of the two dogs on opposite sides of the roller 71, as shown in Fig. 3, will hold segment 105 in a central position; location of the dogs below the roller 71, as seen in Fig. 4, will position the segment 105 in a lower position, and location of the dogs above the roller 71 will raise the segment. There are four pairs of dogs 73, 74 and four segments 105, each segment being engaged with a pinion 133 mounted upon a universal jointed extension of one of the accumulator shafts 403, and the position of the segments by the dogs above described provides the three positions of radial adjustment of the shafts 403 and the cams carried thereby. In the machine illustrated however only two adjusted positions of the parts are taken by the devices related to the No. 3 and No. 4 accumulators, since the plungers thereof are not adapted for intermediate adjustment. When the plungers 84 of these accumulators meet an unperforated portion of the tube 82, the cams 135 will be positioned with their flat faces 136 opposite the pawls 137, providing for a non-add adjustment of the accumulators, while movement of a plunger 84 into a perforation of tube 82 will move the cams 135 into position to cooperate with the pawls 137, providing for addition on the related accumulator.

The cams 121 and 122 of the No. 1 and No. 2 accumulators are arranged in different angular position upon their shafts. That is to say from a position of adjustment of the shaft 403 wherein neither cam 121 nor 122 is in active position, a one-third rotation of the shaft 403 of the No. 1 accumulator in a counter-clockwise direction as viewed in Fig. 2 will bring the cam 122 into active position, whereas a similar movement of the shaft 403 of the No. 2 accumulator will bring the cam 121 into active position. This one step of counter-clockwise movement is effected by movement of a plunger 83 from its non-add position, against the unperforated surface of tube 82, into its mid-

way position, in which the shoulder of the plunger engages the marginal wall of a small hole of the tube 82. The effect is to set the No. 1 accumulator into subtracting position and the No. 2 accumulator into adding position. A second step of 5 counter-clockwise adjustment of these shafts 403 will render the adding cam 121 of the No. 1 accumulator active and the subtracting cam 122 of the No. 2 accumulator active, this being the position taken upon movement of the plungers 83 into 10 the large perforations of the tube 82, and also being the position of the cams illustrated in Fig. 2. All of the mechanism heretofore described is disclosed in the Patents 1,932,013 and 1,946,572, hereinbefore referred to, but the opposite arrangement of the cams 121 and 122 of the No. 1 and No. 2 accumulators is novel, and has been combined with the program modifying means now to be described for effecting certain new results. 20

Program modifying devices

Means are provided whereby the operator may modify the adjustment of certain of the accumulators called for by the program mechanism in any particular tabulated position of the record 25 carriage.

For this purpose a cylinder 380 (Figs. 3, 5 and 7) is rotatably mounted in the frame of the machine, said cylinder being notched as at 381 to provide seats for the stop lugs 382 of slides 383. 30 Normally these slides are held out of contact with the cylinder 380, by means of a lever 385 having a spring 386 adapted to hold an arm 387 of said lever against lugs 388 of the slides. Lever 385 extends above the keyboard of the machine, and 35 when moved rearwardly by the operator, against the tension of the spring 386, springs 384 of the slides 383 are tensioned and will serve to move the slides downwardly into contact with the cylinder 380. If cylinder 380 has been adjusted so 40 that a notch 381 is below one of the lugs 382, the related slide 383 will be allowed to move downwardly into its operative position, in which the lower end of the slide will lie in the path of movement of a pin 389 extending above the pivotal points of junction of the levers 86 with the links 96. Should no notch 381 of cylinder 380 lie below a lug 382 of a slide 383, said slide will be held in inoperative position, above the path 45 of movement of the related pin 389. 50

There are two series of slides 383, comprising a rearward series lying adjacent the pins 389, and adapted to prevent movement of the feelers beyond their position of contact with the tube 82. The slides 383 of the forward series are spaced 55 from the related pins 389 by distance corresponding to the movement of the feeler plungers into contact with the marginal walls of the small perforations of the tube 82. Therefore, the slides 383 of the rearward series are adapted to hold 60 the feelers in non-add position, while the slides 383 of the forward series are adapted to hold the No. 1 accumulator in adding position regardless of whether the feeler plungers register with a 65 small or with a larger perforation of tube 82.

In the machine illustrated, slides 383 are provided for the feelers of the No. 1 and No. 2 accumulators, and the guide rods 390 between which the slides are mounted are provided with seats 70 for slides 383 related to the No. 3 and No. 4 accumulators, and designed to hold such accumulators in non-add position. Such additional slides 383 would be duplicates of the slides of the rearward series related to the No. 1 and No. 2 ac-

cumulators, and would not necessarily be provided in any given machine.

The cylinder 380 is provided with notches 381 opening in different angular positions about the axis of the cylinder, so that rotation of the cylinder, by means of a hand knob 391 will bring different combinations of notches under the lugs 382 of the slides. The tube 82 is adjustable into different angular positions, to bring different series of perforations in line with the plungers 83, 84, so that different programs are provided for, these programs being customarily numbered upon the tube adjusting members. Similar numbers may be applied to the knob 391, so that the cylinder 380 may be set into position to correctly modify any selected program.

Vertical total

As an illustration of the utility of the program modifying mechanism, let it be assumed that it is desired to print and accumulate credit items in the No. 3 and No. 4 accumulators; debit items (registered complementally) in the No. 2 accumulator; cross footings in the No. 1 accumulator, and thereafter to print the totals accumulated in the No. 2, 3 and 4 accumulators separately and to print the algebraic sum of these totals as a grand total. This may all be done, in the structure disclosed herein, and without the addition of a grand total accumulator. After the entry of the items and the printing thereof in the appropriate columns of the record sheet, the vertical totals in the No. 2, 3 and 4 accumulators are transferred, each as it is printed at the foot of the related column, to the No. 1 accumulator or cross footer, from which the grand total may thereafter be printed. The following table will show first the plus (+), minus (-) and non-add (N. A.) settings of the accumulators (Nos. 1, 2, 3 and 4) in accordance with the control of the program mechanism, during the accumulating and cross footing (T) operations; second, the setting of the same accumulators in the various columns during the vertical total taking (T) and the total transfer (Tr.) and the grand totaling operations (Vertical total program, Cross footing column), and third, the changes of setting necessary in the different accumulators in the respective columns in passing from the Accumulating program to the Vertical total program:

	Credit column	Debit column	Credit column	Cross footing column
55 Accumulative program...	No. 3+ No. 1+ Nos. 2, 4, N. A.	No. 2- No. 1- Nos. 3, 4, N. A.	No. 4+ No. 1+ Nos. 2, 3, N. A.	No. 1+ = T. Nos. 2, 3, 4, N. A.
Vertical total program...	No. 3+ = T. No. 1- = Tr. Nos. 2, 4, N. A.	No. 2+ = T. No. 1- = Tr. Nos. 3, 4, N. A.	No. 4+ = T. No. 1- = Tr. Nos. 2, 3, N. A.	No. 1+ = T. Nos. 2, 3, 4, N. A.
60 Change.....	No. 1+ to -	No. 2- to +	No. 1+ to -	None.

In effecting these settings, plungers 84 of the No. 3 and No. 4 accumulators will be opposite imperforate portions of the tube 82, except that in the first column the No. 3 accumulator plunger will be opposite the large perforation and in the third column the No. 4 accumulator plunger will be opposite the larger perforation. Likewise the No. 2 accumulator will act only in the second

column, wherein its plunger 83 will be opposite the large perforation. The No. 1 accumulator plunger will be opposite the large perforation in the first, third and fourth columns and opposite a small perforation in the second column. The changes of the No. 1 and No. 2 accumulators when the vertical totals are taken in the first three columns will be effected, upon adjustment of lever 385 by the operator, by blocking out the plungers of these accumulators by means of the slides 383 of the forward series, thereby limiting the plungers to a movement corresponding to that allowed by the small perforations of the tube 82.

I claim:

1. In a listing calculator having a transversely shiftable record carriage and a plurality of accumulators: the combination with control means adapted to differentially control the activity and sign character of registrations upon said accumulators in different columnar positions of the carriage in accordance with a predetermined programme, including a graded abutment member mounted upon the carriage, a series of feeler devices movable into contact with said abutment member, and means whereby a given degree of movement of any one of said feeler devices will effect a change of control in the related accumulator, of a selectively settable series of graded control surfaces mounted in fixed relation to said feelers, and manipulative means movable under control of the appropriately set control surfaces into the paths of movement of said feeler devices.

2. In a listing calculator having a transversely shiftable record carriage and a plurality of accumulators: the combination with control means adapted to differentially control the activity and sign character of registrations upon said accumulators in different columnar positions of the carriage in accordance with a predetermined programme, including a graded abutment member mounted upon the carriage, a series of feeler devices movable into contact with said abutment member, means whereby a given degree of movement of one of said feeler devices will effect a change of control from minus to plus registration in one accumulator, and means whereby a similar degree of movement of another feeler device will effect a change of control from plus to minus reg-

istration in another accumulator, of manually controlled means movable into the path of movement of said feeler devices and further means settable to determine the movement of said movable means to modify the control of said feeler devices.

LORING PICKERING CROSMAN.
